UNITED STATES PATENT OFFICE.

PAUL L. MARDIS, OF ALTOONA, PENNSYLVANIA, ASSIGNOR TO WESTINGHOUSE ELECTRIC AND MANUFACTURING COMPANY, A CORPORATION OF PENNSYLVANIA.

CONTROL SYSTEM.

1,266,607.

Specification of Letters Patent. Patented May 21, 1918.

Application filed May 3, 1915. Serial No. 25,496.

To all whom it may concern:

Be it known that I, PAUL L. MARDIS, a citizen of the United States, and a resident of Altoona, in the county of Blair and State 5 of Pennsylvania, have invented a new and useful Improvement in Control Systems, of which the following is a specification.

My invention relates to control systems for dynamo-electric machines, and it has 10 special reference to four motor equipments of the series-parallel type such as are commonly employed upon electric railway vehicles.

One of the objects of my invention is to 15 provide an improved method and means for controlling the operation of a plurality of motors constituting a portion of a system of the above-indicated character, and to provide a simple mode of successively arranging 20 the circuit connections of the motors for series, series-parallel and parallel-circuit operation, while maintaining a unidirectional flow of current through the motors during the circuit changes.

Another object of my invention is to provide a method and means for controlling a 25 four-motor equipment of the general class referred to which shall be adapted to disconnect each of the respective motors from 30 the system during the several steps by which the motors are accelerated to their full-speed operation, whereby each of the motors is permitted to remain idle for a portion of the accelerating period.

Another object of my invention is to provide a method and means for changing the 35 several motors from series-parallel groups into full-parallel-circuit relation through an intermediate step in which a single motor is 40 connected in parallel with two motors that are connected in series-circuit relation, and, moreover, for effecting these changes in circuit connections without reversing the current in any of the motors.

In the prior art, it has heretofore been 45 proposed to provide a system and mode of control of somewhat similar characteristics, but, in all such systems with which I am familiar, the desired circuit changes are effected 50 at the expense of reversing the direction of flow of the current in certain of the motors, and the motors are not worked uniformly during the acceleration period, certain of the motors being actively in circuit

throughout the entire acceleration, while 55 other motors are permitted to be idle to some extent.

According to my invention, I propose to improve and simplify the systems of the prior art, to overcome the difficulties and 60 deficiencies incident to other systems and to secure the advantages and benefits herein-before enumerated.

My invention is illustrated in the accompanying drawings in which Figure 1 is a 65 diagrammatic view of the main circuit connections and main control apparatus of a system of control embodying my invention; Fig. 2 is a sequence chart indicating the 70 positions of the several switches in different steps of the controller; Fig. 3 is a diagrammatic view of the auxiliary control circuit connections and the auxiliary control circuit apparatus which is employed for governing 75 the operation of the main circuit apparatus shown in Fig. 1; Fig. 4 is a diagrammatic simplified view of the main circuit connections of the motors that are established in certain steps of the controller; and Figs. 5 and 6 are, respectively, views corresponding 80 to Figs. 2 and 4 of a modified form of control system embodying my invention.

Referring to Fig. 1, a plurality of series motors M1, M2, M3 and M4 are adapted to receive energy from a supply circuit, one 85 member of which comprises a trolley conductor 1 and the other, a ground G, through a resistor R and a plurality of electrically operated motor-circuit switches a, b, c, d, e, f, g, h, i, j, and k, which are adapted to 90 arrange the circuit connections of the several motors for series, series-parallel and full-parallel operation.

The several unit switches may be of any well-known construction and each comprises 95 an energizing coil 3, a movable magnetizable core 4, a movable switch member 5 and a plurality of stationary contact terminals 6 which are adapted for co-operative engagement, while some of the unit switches referred to are provided with interlock switches 7 by means of which certain of the control circuits are interlocked and a predetermined sequence of operation is obtained. The unit switches may be, and preferably 100 are, of the well-known electro-pneumatic type.

Hereinafter, for the sake of simplicity,

the several unit switches will be referred to, as a whole, by their reference characters and no attempt will be made to designate the component parts of each switch with separate reference characters.

It will, of course, be understood that each of the switches is adapted to occupy two positions, an "in" position, in which the switch is energized and closed, and an "out" position, in which it is deenergized and opened. The interlock switches associated with the several unit switches will be denoted by means of the reference character of the unit switch with which it is associated, followed by the word "in" or "out," which indicates the position in which the interlock switch is closed. For instance, interlock switch *i*-out indicates that the interlock switch associated with the unit switch *i* is closed when said unit switch occupies its open or "out" position.

Referring now to Fig. 3, a master controller MC is shown, which comprises a movable contact member 10 of peculiar configuration and a plurality of stationary contact terminals *B*+, *a*', *b*', *c*', *d*', *e*', *f*', *g*', *h*', *i*', *j*' and *k*' that are adapted to be engaged by the movable contact member 10 along the position-indicating lines 1, 2, 3, 4, 5, 6, 7 and 8 for the purpose of establishing suitable circuits from a battery *B*, or other source of energy, through the energizing coils of the several unit switches *a* to *k*, inclusive.

Assuming the apparatus and circuit connections to be as shown, the operation of the system is as follows: The master controller MC is first moved into its position 1 in which a circuit is established from the positive side of the battery *B* which includes stationary contact terminal *B*+ and movable conducting segment 10 of the master controller MC where the circuit divides, one branch including contact terminal *a*' and energizing coil of switch *a* and thence to a conductor *B*- which connects to the negative side of the battery; another circuit traverses contact terminal *b*', energizing coil of switch *b*, and interlock switch *i*-out to the *B*- conductor; another circuit traverses stationary contact terminals *c*', energizing coil of switch *c*, and interlock switch *j*-out to the *B*- conductor, and a fourth branch includes contact terminal *d*', energizing coil of switch *d*, and interlock switch *k*-out to the *B*- conductor.

Having established the circuits just traced, the several unit switches *a*, *b*, *c*, and *d* are energized and closed. Thus, energy is supplied from the supply-circuit conductor *l* through trolley *T*, switch *a*, resistor *R*, motor *M*1, switch *b*, motor *M*2, switch *c*, motor *M*3, switch *d*, and motor *M*4 to the return circuit *G*. The several motors *M*1, *M*2, *M*3, and *M*4 and resistor *R* are thus connected in series-circuit relation, as shown

in step 1 in Fig. 4, and, being supplied with energy, are started into operation at slow speed.

When the master controller MC is moved to its position 2, another circuit is established from the movable contact member 10 through contact terminal *e*' and energizing coil of switch *e* to the conductor *B*-.

The switch *e* is, therefore, energized and closed to short-circuit the accelerating resistor *R*, thereby causing the motors to increase in speed, the circuit connections being as shown in step 2 of Fig. 4.

During the next step of the controller MC, circuits are established from conducting member 10 through contact terminal *h*' and energizing coil of switch *h* to conductor *B*-, and through contact terminal *i*', and energizing coil of switch *i* to the interlock switch *b*-out. The switch *h* is thus energized and closed, although switch *i* is not energized, inasmuch as its circuit is broken by the interlock switch *b*-out, switch *b* being still held in its "in" or "closed" position. Immediately subsequent to this action, the stationary contact terminals *b*' and *d*' become disengaged from the movable conducting member 10 and, therefore, the corresponding switches *b* and *d* are deenergized and permitted to open. As soon as the switch *b* drops into its "out" position, its interlock switch *b*-out completes the energizing circuit of the switch *i*, and said switch immediately is closed.

The main circuit through the motors is then as follows: from trolley *T* through switch *a*, switch *e*, motor *M*1, switch *i*, switch *c*, switch *h* and motor *M*4 to the ground *G*, as shown in step 3 of Fig. 4. Motors *M*2 and *M*3 are disconnected from active circuit and are permitted to remain idle.

As the master controller is moved into position 4, circuits are established from contact member 10 through contact terminal *f*' and energizing coil of switch *f* to conductor *B*-, and through contact terminal *k*', energizing coil of switch *k* and interlock switch *d*-out to the *B*- conductor. Switches *f* and *k* are thus energized and closed, thereby connecting the several motors *M*1, *M*2, *M*3 and *M*4 in series-parallel groups, as indicated in step 4 of Fig. 4.

The new motor circuit established by the closure of the switches just referred to, supplies energy to motors *M*1 and *M*4 through a circuit from the trolley through switch *f*, motor *M*2, switch *c*, motor *M*3 and switch *k* to ground *G*.

Between positions or steps 4 and 5 of the master controller MC, there are a plurality of transition notches 4*a*, 4*b*, 4*c* and 4*d*, as indicated in the chart shown in Fig. 2, for the purpose of effecting the transition of motor-circuit connections from the series-

parallel relation of the motors, as established in position 4, to the next operative step or position 5 without the interruption of the motor current. Inasmuch as any suitable transition connections may be employed between steps 4 and 5, so long as the motor circuits are not interrupted and a unidirectional flow of current through the motors is maintained, I do not deem it necessary to trace the circuit connections of the various transition notches. Therefore, a description of the transition connections will be omitted and the connections established in the next running position 5 will be considered.

In this position, the movable conducting member 10 is in engagement with the following stationary contact terminals B+, a', b', e', g', j' and k' and, therefore, the corresponding switches a, b, e, g, j, and k are closed to establish the arrangement of motors indicated in step 5 of Fig. 4. The circuit connections are as follows: from trolley T through switch a, and switch e, where the circuit divides, one branch including the motor M1, switch b, motor M2, and switch j to the ground G, and the other branch including switch g, motor M3 and switch k to the ground G. The motor M4 is therefore disconnected and idle.

In the step 6 of the controller MC, stationary contact terminal h' and its corresponding switch h is energized, as will be understood. The switch h, therefore, is closed and connects the motor M4 in parallel with the motor M3, both of which are in multiple-circuit relation with the motors M1 and M2 which are in series with each other. The arrangement of circuit connections and motors is shown in step 6 of Fig. 4.

In moving the master controller to its position 7, contact terminal b' becomes disengaged from the movable conducting member 10 and, hence, the switch b is deenergized and opened. Concurrently, therewith, however, contact terminal f' becomes energized and its corresponding switch f closed. Thus, the motor M1 is disconnected from the system and is idle, while motor M2 is connected in parallel relation with the other two parallel-connected motors M3 and M4. The circuit connections are then as shown in step 7 of Fig. 4.

As the master controller MC is moved into its last position 8, contact terminal i becomes disengaged and its corresponding switch i is closed to connect the motor M1 in parallel with the other motors M2, M3 and M4, whereby the full-parallel arrangement of the motors is established.

Throughout the operation, as hereinbefore set forth, it is manifest that, at no time, is a reversal in the direction of flow of current through any of the motors effected, but that a unidirectional flow thereof is maintained

at all times. Moreover, each one of the several driving motors is disconnected from the system and permitted to be idle for a certain period of time, whereby the several motors are worked substantially uniformly and each of them is relieved at different intervals.

Reference may now be had to Figs. 5 and 6 which disclose a modified form of my invention in which the sequence of the switches shown in Fig. 1 is so fixed as to effect the changes in circuit connections from series-circuit relation to full-parallel relation, while maintaining a unidirectional flow of current through said motors throughout the circuit changes.

In step 1, switches a, b, c, and d are closed and the motors M1, M2, M3 and M4 and the starting resistor R are connected in series-circuit relation, as shown in step 1 of Fig. 6.

In step 2, switch e is also closed to short-circuit the resistor R and exclude it from the motor circuit.

In step 3, switch G is closed and switch c opened, thereby disconnecting the motors M1 and M2 and connecting motors M3 and M4 in series circuit directly across the source of energy.

Switch J is closed in position 4 to connect the negative side of the motors M1 and M2 to ground, thereby establishing a series-parallel grouping of the motors.

In the next or transition position, switch b is opened and switch f closed. Thus, the motor M1 is disconnected from circuit and motor M2 is connected in parallel-circuit relation to motors M3 and M4 which are connected in series circuit with each other.

In step 5, switch e is opened and switch i closed, thereby temporarily inserting the resistor R and connecting the motor M1 in parallel with the motor M2, said motors being arranged in multiple-circuit relation with the series-connected motors M3 and M4.

In step 6, switch e is again closed to include the resistor R, the other circuit connections remaining unchanged.

In step 7, switch d is opened and switch k closed. Thus, the motors M1, M2 and M3 are connected in multiple relation and motor M4 is disconnected from the system.

In the last step, step 8, switch h is closed to connect the motor M4 in parallel with the other motors, thereby establishing connections for full-parallel operation.

By reason of the fact that a master controller and auxiliary-control-circuit connections have been fully set forth in connection with the system first described, and also, inasmuch as it is believed that no difficulty will be experienced by those skilled in the art in understanding the mode of operation and circuit connections of the modified form of my invention just described, I have deemed it unnecessary to illustrate a master controller for the purpose of governing the

several switches to secure a sequence of operation thereof in accordance with the chart shown in Fig. 5, whereby the circuit connections shown in Fig. 6 are established.

5 It is manifest, of course, that various modifications in the arrangement of circuit connections and mode of operation may be effected without departing from the spirit and scope of my invention, and such modifications are intended to be covered by the appended claims.

I claim as my invention:

1. The method of controlling four electric motors which consists in connecting said 15 motors in series relation, disconnecting two of the motors from circuit, connecting the motors in series-parallel groups, connecting two of the motors in series-circuit and in parallel relation to a single motor, and connecting the motors in full-parallel relation, while maintaining a unidirectional flow of current during the changes.

2. In a system of control, the combination with four motors, of control apparatus associated therewith for arranging the circuit connections of the several motors to change the motors from series to parallel relations and to effect the changes by successively establishing as many parallel paths through 30 the motors as there are motors, while maintaining the flow of current through each of the active motors unchanged, said changes including one transition step wherein two series-connected motors are in multiple circuit 35 with a single motor.

3. In a system of control, the combination with a plurality of motors, of means comprising control apparatus and circuit connections for connecting the motors in series, 40 in series-parallel and in parallel relation, and means for disconnecting each of said motors from circuit during the acceleration from series to parallel relation and for maintaining at least two of said motors in circuit 45 throughout the changes.

4. The method of changing four electric motors from series-parallel relation to full-parallel relation, which consists in first cutting-out one of the said motors, leaving one 50 motor in parallel with the two which are in series, then reconnecting the motor which is cut-out in parallel with the remaining motors, then cutting-out one of the two motors in series, and finally connecting the 55 last motor cut-out in parallel with the others, while maintaining a unidirectional flow of current through the respective motors.

5. In a control system, the combination 60 with a plurality of motors, of control apparatus for first connecting all of the motors

in series relation, then connecting them in series-parallel groups, and finally all in parallel relation, said control apparatus comprising relatively movable contact members 65 and circuit connections arranged to disconnect the motors one after another from circuit, while effecting the motor circuit changes and to maintain a unidirectional flow of current through the respective motors. 70

6. In a system of control, the combination with a plurality of electric motors, of control apparatus comprising contact members and circuit connections for changing the 75 motors from series-parallel relation to full-parallel relation, said contact members and connections being adapted to successively disconnect the motors, one after another, from circuit, and to maintain a unidirectional 80 flow of current through the active motors during the circuit changes.

7. The method of control of four electric motors, which consists in connecting all of said motors in series-parallel groups, then 85 connecting two series-connected motors in multiple circuit with a single-motor, and then connecting all of the motors in parallel-circuit relation, while maintaining a unidirectional flow of current through said 90 motors during the operation.

8. The method of controlling four electric motors, which consists in successively connecting the motors in series-circuit relation, in series-parallel groups and in full-parallel-circuit relation, while idling all of said 95 motors at different times during the changes in connections.

9. The method of controlling four electric motors, which consists in successively connecting said motors in series-circuit relation and then in full-parallel-circuit relation, while disconnecting all of the motors from circuit and idling the same at different times 100 during the changes in connections. 105

10. In a system of control, the combination with a plurality of electric motors, of control apparatus and circuit connections for successively connecting the motors in series-circuit relation, in series-parallel 110 groups and in full-parallel-circuit relation, while disconnecting all of the motors from the system at different times and allowing them to remain idle during the circuit changes. 115

In testimony whereof, I have hereunto subscribed my name this 27th day of April, 1915.

PAUL L. MARDIS.
